UNITED STATES PATENT OFFICE

2,092,807

FASTENING

Fred N. La Chapelle, Beverly, Mass., assignor to
United Shoe Machinery Corporation, Paterson, N. J., a corporation of New Jersey

Application July 29, 1936, Serial No. 93,253

3 Claims. (Cl. 85—49)

This invention relates to improvements in fastenings and is herein illustrated as embodied in staples formed from twisted paper impregnated with glue.

5 Staples formed of felted fibrous material, such as paper, of the type disclosed in United States Letters Patent No. 1,957,216, granted May 1, 1934, upon an application filed in the name of Fred N. La Chapelle have been used successfully as effective fastenings for securing together work pieces of leather or other materials, particularly in the manufacture of boots and shoes. However, under certain conditions difficulty has been experienced in maintaining the staples permanently in position. Instances of this have occurred, for example, in securing an insole or middle sole to the upper of a stitchdown shoe particularly where the sole is of flimsy material such as soft paper which does not provide sufficient anchorage for the staples, or where the sole is coated with wax or other stiffening material in which case the glue on the staple does not grip as well as would otherwise be the case. These difficulties are aggravated in cases where, for the sake of economy, the shoe manufacturer allows only a small lasting margin on the upper with the result that the upper has to be stretched over the last under great tension. This results in applying an unusual amount of stress to the staples which secure the marginal portion of the upper to the sole and frequently results in breaking the legs of the staple after the glue has set or in pulling the staple loose from the sole.

In view of the foregoing, it is an object of the present invention to provide an improved fastening by the use of which the difficulties above mentioned will be overcome. Accordingly, and as illustrated, I have provided a fastening having an outer layer of felted fibrous material impregnated with stiffening material and having a reinforcing metal core. Preferably and as shown, the outer layer is composed of twisted paper impregnated with glue and the core consists of wire made of soft iron or other soft metal.

45 Staples constructed as above outlined are advantageous in that when they are driven into the parts which they are to secure together and the legs of the staples are deflected the wire core 50 will tend to hold the staple in position and resist forces which might tend to pull the staple out of the material or to break the legs of the staple. Furthermore, the core, being of soft metal, will not interfere with subsequent stitching operations. That is, if the needle should engage the

core of the staple the needle will not be deflected or broken.

It is to be understood that while the invention is illustrated herein in connection with a staple construction the invention is not so limited since it is apparent that other types of fastenings such as, for example, pegs, could be formed of fastening material of the type above described and provided with a wire reinforcing core.

These and other features of the invention are disclosed in the accompanying drawing, described in the following detailed specification, and pointed out in the claims.

The drawing is a diagrammatic view on a much enlarged scale in which—

Fig. 1 illustrates a side view partly in section of a staple constructed in accordance with one embodiment of the invention;

Fig. 2 illustrates a cross section through one leg of the staple; and

Fig. 3 is a side view of the fastening material from which the staple is made.

The staple illustrated in Fig. 1 comprises a cross bar 10 and two depending legs 12, the shape of the staple being substantially that of an inverted U. The staple is made from a length of fastening material, Fig. 3, comprising a metallic core 14, preferably of soft iron wire, about which is twisted an outer layer of felted fabric material 16 such as paper impregnated with glue during the twisting operation. The material may be about .040 of an inch in diameter with an iron wire core about .009 of an inch in diameter although other dimensions may also be used. The manufacture of the fastening material can be conveniently accomplished by use of a machine such as that disclosed in United States Letters Patent No. 1,837,433, granted December 22, 1931 upon an application filed in the name of Alex Hayner, suitably modified to advance and to twist a paper strip around a separately advanced wire. After the material has formed it may readily be further operated upon to form staples by the use of a machine of the type illustrated in the aforementioned La Chapelle Letters Patent No. 1,957,216.

In operation, the staples are driven through the parts which they are to secure together, preferably while the parts are held under pressure, the glue with which the outer layer of the staple is covered being moistened so that the legs of the staple will grip the material after the glue is set, and the staple legs are deflected toward the surface of the work piece through which they pass with the result that the wire reinforcing core

near the points where the legs pass through the work is bent at an angle to the direction of drive. This materially contributes to the holding power of the staple and further increases the tensile strength of the legs of the staple against a direct pull thus avoiding any likelihood of breaking the legs of the staple or of pulling the staple from the work.

Having described the invention, what I claim as new and desire to secure by Letters Patent of the United States is:

1. A fastening comprising a core of wire covered throughout its entire length with twisted felted fibrous material sized with stiffening material.

2. A staple of felted fibrous material reinforced throughout its entire length with a soft iron wire core.

3. A staple comprising a wire core covered throughout its entire length with twisted paper impregnated with glue.

FRED N. LA CHAPELLE.

10

1. A fastening comprising a core of wire covered throughout its entire length with twisted felted fibrous material sized with stiffening material.

2. A staple of felted fibrous material reinforced throughout its entire length with a soft iron wire core.

3. A staple comprising a wire core covered throughout its entire length with twisted paper impregnated with glue.

FRED N. LA CHAPELLE.
